UNITED STATES PATENT OFFICE.

ANTON C. EGGERS, OF ASTORIA, NEW YORK.

DESIGN FOR A PENCIL-TIP.

SPECIFICATION forming part of Design No. 16,340, dated October 20, 1885.

Application filed July 23, 1885. Serial No. 172,472. Term of patent 7 years.

To all whom it may concern:

Be it known that I, ANTON C. EGGERS, of Astoria, in the county of Queens and State of New York, have invented and produced a new and original Design for Pencil-Tips, of which the following is a full, clear, and exact description.

Reference is to be had to the accompanying drawings, forming part of this specification, to which similar letters of reference indicate corresponding parts in both the figures.

Figure 1 is a side elevation of my newly-designed pencil-tip, and Fig. 2 is a plan view thereof.

15 The leading feature of my design for a pencil-tip consists of a conical top piece, a portion of substantially cylindrical form, and an intermediate enlargement of mutilated circular form, as hereinafter described, and pointed out 20 in the claims.

a represents the top piece of my newly-designed pencil-tip. This top piece, *a*, is conical, and rises from the center of the enlargement *b*. The enlargement *b* and conical top *a* surmount 25 the substantially cylindrical lower portion, *c*, of the tip, and the enlargement *b* is flattened

at *b'*, and circular and serrated at *b''*, as shown clearly in Fig. 2. The lower substantially cylindrical portion, *c*, is slightly conical or slightly larger at the point where it joins the enlargement *b* than at the lower end, as shown clearly in Fig. 1.

Having thus described my invention, what I claim as new, and desire to secure by Letters Patent, is—

30 1. The design for a pencil-tip herein shown and described, the same consisting of the portion *c*, of substantially cylindrical form, conical top *a*, and intermediate enlargement, *b*, of mutilated circular form, having plain flat surfaces *b'*. 35

2. The design for a pencil-tip herein shown and described, the same consisting of the portion *c*, of substantially cylindrical form, the conical top *a*, and the intermediate enlargement, *b*, having two opposite flat parallel surfaces, *b'* *b''*, and two opposite curved and serrated surfaces, *b''* *b'''*, between the flat surfaces. 40 45

ANTON C. EGGERS.
